UNITED STATES PATENT OFFICE.

DE FOREST LILLIS AND HARVEY A. PIKE, OF NEW YORK, N. Y.

FOLDING CAR-STAKE.

No. 896,031.

Specification of Letters Patent.

Patented Aug. 11, 1908.

Application filed September 18, 1906. Serial No. 335,050.

To all whom it may concern:

Be it known that we, DE FOREST LILLIS and HARVEY A. PIKE, citizens of the United States, and residents of New York city, New York, have invented certain Improvements in Folding Car-Stakes, of which the following is a specification.

Our invention relates to railway cars, and consists of an improved form of folding stake for use with flat cars, which stake is so mounted as to be capable of proper elevation to retain a load in place, and to be folded against the side frame of the car when not in use.

15 A further feature of our invention consists in arranging the stakes to support a board or a series of boards at the sides of the cars and thus form cars of the gondola type, the ends for which can be suitably secured to said 20 sides.

Our invention is fully shown in the accompanying drawings, in which:—

Figure 1, is a perspective view of one form of structure made in accordance with our invention; Fig. 2, is an enlarged perspective view of part of the same; Fig. 3, is a front elevation of a portion of the structure shown in Figs. 1 and 2; Fig. 4, is a view of a detail of the structure shown in Fig. 1; Fig. 5, shows 30 the boss provided with grooves; Fig. 6, is a perspective view similar to Fig. 1, showing a modified form of structure embodying our invention; Fig. 7, is a perspective view similar to Fig. 2, showing part of the structure 35 illustrated in Fig. 6; Fig. 8, is a sectional view in elevation on the line *b*—*b*, Fig. 9, and Fig. 9, is a sectional view on the line *c*—*c*, Fig. 8.

The object of our invention is to provide a 40 folding car stake that may be used as a side support for lumber and material of a similar nature extending lengthwise of the car; such stake being capable of further use as a support for sides to form cars of the gondola 45 type.

In the form of structure shown in Figs. 1 to 5 inclusive, we provide a supporting member 1, which may be readily secured to the side frame 2 of the car by means of bolts, rivets, 50 or other suitable fastenings 3, and which is provided with a hollow projecting part 4, in this instance semi-circular in shape. The car stake proper is shown at 5 and carries a boss 6 at its lower end, which fits the recess

of the supporting member 1. The upper 55 part of this stake is preferably hollow, as shown, and we may provide the same with the strengthening rib 7, if desired. A chain 8 is carried by the stake, fitting within the same when not in use and adapted to be secured to a similar chain carried by a stake on the opposite side of the car, whereby a load may be properly retained in place. The chain is preferably secured to a block disposed within the stake which prevents the withdrawal of said chain. The chain is entered through an aperture 9 in the lower part of said stake.

In order to maintain the stake in the upright position, the boss 6 is grooved at 10 and 70 10^a, as clearly shown in Fig. 5, and a pin 11, passing through apertures 12 in the projecting portion 4 of the supporting member 1, is adapted to engage these grooves and thereby hold the stake against movement. When in 75 position of use said pin will engage the groove 10, but when the stake is folded against the side of the car as shown by dotted lines, Fig. 3, the groove 10^a comes into position for engagement by the pin 11; such pin therefore, serving to hold the stake fixed when either in the operative or inoperative position. In order that the pin may not be lost, we provide a chain 13 whereby it may be secured to the supporting member. 85

In Figs. 6, 7, 8 and 9, we have shown a modified form of structure in which the stake 5^a is provided with a T-head 6^a, instead of the boss shown in the other form of our device. This T-head is adapted to fit within a 90 recess of a supporting member 1^a in a manner similar to the structure shown in Figs. 1, 2, 3 and 4, and is pivotally mounted therein by means of a pin 15. To support this form of stake in the operative and inoperative 95 position, the T-head is grooved at 16 and 16^a, and a pin 11^a is provided which is arranged to engage these grooves; the member 1^a being grooved at 12^a and the pin forming a key to engage the complementary grooved 100 portions and hold the stake in the different positions. When said pin engages the groove 16, the stake will be maintained in the upright position; said groove being formed in one arm of the T-head, while the other arm 105 rests on a ledge 17 within the supporting member 1^a. When said pin engages the groove 16^a, however, the stake will be held

in the inoperative position. This form of the stake is also provided with a rib 7^a substantially the same in character as that shown in Figs. 1, 2, 3 and 4, and it is also 5 hollow and carries the usual chain.

In order that the parts may be readily moved to the operative and inoperative positions, we provide for clearance between the parts, as indicated in Figs. 4 and 9, the 10 pins 11 and 11^a which engage the stakes and hold them in the upright position being tapered and serving to press the ends of the stakes into close engagement with rear wall of the supporting members.

15 As ordinarily used, the stakes simply serve as side guides or guards and supports for loads of timber, lumber, or other material usually of some length and extending lengthwise of the car. They may be further employed to support side boards to form a gondola car, and to this end they are slotted at 20, as clearly illustrated in the drawings, such slots extending from the top to a point near the bottom. The side boards to form the gondola car are provided with bolts 21 having heads 22 which are adapted to fit behind the shoulders formed by the slots of the stakes in the manner shown in Figs. 4 and 9. End sections for engagement with said sides to 30 complete the gondola cars may be secured thereto in any suitable manner.

We claim:—

1. As a new article of manufacture, a stake for cars mounted for rotative movement only so as to be folded against the side of the cars, means for limiting its movement, and a detachable key adapted to engage a groove in the stake to lock the same in vertical and horizontal positions.

40 2. As a new article of manufacture, a hollow stake for cars mounted for rotative movement only so as to be folded against the side of the cars, means for limiting its movement to the active and inactive positions, and 45 a detachable key adapted to engage a groove in the stake to lock the same in said positions.

3. As a new article of manufacture, a hollow folding stake for cars, having a solid end 50 forming a pivotal connection.

4. As a new article of manufacture, a hollow, slotted, folding stake for cars.

5. As a new article of manufacture, a pivotally mounted stake for cars mounted for rotative movement only, a housing for the pivotal end of said stake, and detachable means co-acting with the housing and stake for supporting and positively locking said stake in different positions.

60 6. As a new article of manufacture, a hollow solid-ended stake for cars, having a chain disposed within the same, and retaining means carried by said stake permitting the partial removal of said chain.

65 7. The combination of a car, a supporting

housing secured to the same, a stake pivotally mounted for rotative movement only in said housing, means carried by the housing for limiting the rotative movement of the stake, and detachable means co-acting with the housing and stake for positively holding the latter in the different positions.

8. The combination of a car, a supporting housing secured thereto, a hollow stake pivotally mounted for rotative movement only in 75 said housing, means for limiting the movement of said stake, and detachable means co-acting with said housing and stake for holding the latter in different positions.

9. The combination of a car, a supporting 80 housing secured thereto, a hollow stake having a closed end pivotally mounted in said housing, and a chain carried by said stake and lying within the same when not in use.

10. The combination with a car, of a sup- 85 . porting member secured thereto, a stake pivotally mounted in said member and capable of movement to the active and inactive positions, and a pin adapted to pass through said member in engagement with the stake to se- 90 cure the latter in its several positions.

11. The combination with a car, of a sup- 95 . porting housing secured thereto and having a semi-spherical recess, a stake having a semi-spherical boss fitting said recess, and means coacting with said support and stake for holding the latter in different positions.

12. The combination with a car, of a sup- 100 . porting member secured thereto and having a semi-circular hollow recess, a stake having a semi-circular boss fitting said recess, said boss having grooves in its face, and a pin adapted to pass through said supporting member and engage said grooves whereby the stake may be held in the operative and 105 inoperative positions.

13. The combination with a car, of a sup- 110 . porting member secured thereto and having a hollow recess, a stake having a projection fitting said recess, said projection having grooves in its face, and a pin adapted to pass through said supporting member and engage said grooves whereby the stake may be held in different positions.

14. The combination with a car, of a hol- 115 . low stake mounted thereon, said stake having its inside wall slotted, means for supporting said stake in an upright position, and side members having headed bolts adapted to engage said stake, said members being 120 adapted to be dropped into place with the heads of the bolts passed behind the shoulders formed by the walls of said slot.

15. The combination with a car, of a sup- 125 . porting member secured thereto and having a recess, a stake having an end arranged to fit said recess, said end being grooved, and a pin adapted to engage the supporting member and either groove of said stake whereby the latter may be held in the different positions. 130

16. The combination with a car, of a hollow stake, a housing carried by the car in which said stake is movable, and a chain carried by said stake and lying within the same 5, when not in use, said stake having an opening near its lower end on the side disposed toward the car for the insertion of said chain.

In testimony whereof, we have signed our

names to this specification, in the presence of two subscribing witnesses.
